UNITED STATES PATENT OFFICE.

HOWARD PARKER, OF NASHUA, NEW HAMPSHIRE, ASSIGNOR TO IMPROVED PAPER MACHINERY COMPANY, OF NASHUA, NEW HAMPSHIRE, A CORPORATION OF MAINE.

METHOD OF MAKING PRESS-ROLLS.

973,380.

Specification of Letters Patent. Patented Oct. 18, 1910.

Application filed January 20, 1910. Serial No. 539,054.

To all whom it may concern:

Be it known that I, HOWARD PARKER, a citizen of the United States, and a resident of Nashua, in the county of Hillsboro and 5 State of New Hampshire, have invented certain new and useful Improvements in Methods of Making Press-Rolls, of which the following is a specification.

This invention relates to the manufacture 10 of press rolls which are used in various manufacturing operations, the roll herein described being designed especially for use in pulp and paper manufactories.

Rolls made in accordance with this invention 15 are designed to take the place of the wooden rolls heretofore used which have been turned up out of a solid block of wood. These old solid rolls are difficult to obtain to-day in the required sizes; they are also 20 apt to splinter and as they are used in places where they are continually subjected to action of water or other fluids they are very apt to crack and become useless. In these solid rolls the grain of course runs length- 25 wise of the roll, making the surface of the roll softer than would be the case if the grain of the wood extended radially of the roll.

Figure 1 is a side elevation partly in section of a roll made in accordance with my 30 invention. Fig. 2 is an end view of the same. Fig. 3 is a detail transverse section on enlarged scale with one of the binding rings broken away and showing the parts in 35 position ready for the last step of the process. Fig. 4 is a view similar to Fig. 3 but showing the finished roll.

By the invention which will now be described I am enabled to build up a roll having 40 a metallic or a similar rigid core and a solid continuous and uniform surface which will retain its shape under all usual conditions of use. In building up a roll according to my invention I make use of 45 a rigid metallic core *a*. To one end of this core I secure an end-ring *b* through which pass binding-rods *c* which extend length- 50 wise of the core. Wedge-shaped blocks of wood or other suitable expansible material 55 *d*, which for convenience will be referred to as sectors, are seated on the core and arranged end to end in such a way that the completed covering appears to be made up of a number of annular sections, each section being composed of a number of these

wooden sectors. The sectors as they are assembled on the core are in their normal unexpanded condition and the inner corners of the sectors of each annular section are located near to and preferably just in 60 contact with each other, while the outer corners are separated by a considerable space. The opposing ends of these sectors are oppositely recessed as at *e* to form a seat on which the binding-rods rest. At intervals 65 throughout the length of the roll binding-rings *f* are placed between the adjacent annular sections, these binding-rings having a bearing on the core, and apertures 70 through which the binding-rods pass. An 70 end-ring is secured to the opposite end of the core and receives the binding-rods. By means of nuts on the ends of the binding-rods the annular sections can be securely 75 clamped between the end-rings. The roll 75 as thus built up is now submerged in water and left there for a sufficient length of time to allow the sectors to expand as much as possible. The annular sections being clamped together by the binding rods without allowing 80 for the expansion of the sectors length- 80 wise of the roll, it will be seen that the sectors as they swell or expand are under a heavy compression which insures the complete closure of all spaces between these 85 annular sections.

The size of the sectors is such that their combined arcs when in normal unexpanded condition are less than the finished circumference of the roll and when expanded 90 greater than the finished circumference of the roll. It results therefore that in this expanding movement due to the immersion of the roll in water the spaces between the sectors of each annular section are completely 95 filled and the sectors are under a heavy compression circumferentially. This insures that all spaces between the ends of the sectors of each annular section are completely closed. 100

The binding-rings prevent the buckling of the binding-rods and because of the wedge- 105 shape of the sectors tend to clamp them firmly onto the core during the expanding operation.

After the roll has been submerged for a sufficient length of time to insure the expansion of the sectors to the limit it is removed and its surface turned down and smoothed off. As thus built it is in the condition in 110

which it is to be used so that the effect of the water which comes in contact with it during its use will not injure the surface of the roll in any way, but on the other hand 5 tends to keep it in its proper condition.

I claim:—

The herein described method of providing a covering for a roll having a rigid core, which consists in locating upon said core, 10 and adjacent to one another, members of

expansible material; fixing said members in relative radial and lengthwise position; and subjecting them to conditions tending to produce expansion, whereby said members are put under a compression strain of both 15 circumferential and lengthwise character.

HOWARD PARKER.
